UNITED STATES PATENT OFFICE.

FRANK HIRSCH, OF STOCKHOLM, SWEDEN.

BELT-SHIFTER.

SPECIFICATION forming part of Letters Patent No. 693,969, dated February 25, 1902.

Application filed August 29, 1900. Serial No. 28,477. (No model.)

To all whom it may concern:

Be it known that I, FRANK HIRSCH, engineer, a subject of the King of Sweden and Norway, and a resident of Stockholm, in the Kingdom 5 of Sweden, have invented new and useful Improvements in Belt-Shifters, of which the following is a specification, reference being had to the accompanying drawings.

This invention relates to improvements in 10 belt-shifters, and has for its object the production of a belt-shifting device by means of which the shifting of a belt from one pulley to another or from one portion of a stepped pulley to another portion thereof may be readily 15 and conveniently accomplished from below where the pulleys are located at a considerable elevation, such as close up to the ceiling in high workshops.

To this end the invention consists of certain 20 novel features of construction, combination, and arrangement of parts, as will be herein-after more fully described, and particularly pointed out in the appended claim.

In the accompanying drawings, Figure 1 is 25 a side elevational view of a belt-shifter embodying my invention, showing the same mounted in position for use. Fig. 2 is a top plan view of the same detached and on an enlarged scale. Fig. 3 is a rear end elevation. 30 Fig. 4 is a vertical longitudinal section.

Referring now more particularly to the drawings, wherein like reference characters designate corresponding parts throughout the several views, the numeral 1 represents a vertical oscillatory support consisting of a rod 35 or bar journaled at its lower end in a bracket 2, secured to the frame of the machine or part to be driven—such as a lathe, as shown in the present instance—and at its upper end in a shelf, bar, or bracket 3, located at a suitable 40 elevation above such machine, and 4 represents a drive-belt running over pulleys 5 and 6, arranged, respectively, on the machine element and on a drive-shaft 7, journaled in 45 hangers 8, depending from said shelf. It will of course be understood that the belt may be arranged to coöperate with fast and loose pulleys in connection with an ordinary single pulley or a stepped pulley, as desired, the manner 50 of mounting the gearing in this particular being immaterial to the operation of the invention. The rod 1 is provided in close

proximity to the machine with a handle 1^a, whereby it may be turned.

Upon the rod or bar 1 is mounted adjacent 55 to the pulley 6 the belt-shifting device, which in the form shown in the drawings, comprises a frame composed of two parts—to wit, an adjustable section 9 in the form of a pair of parallel rods carrying at one end a 60 loop 10 to receive one stretch or run of the belt and a fixed section 11 in the form of a cross-head slidably mounted by eyes 12 upon said rods and provided with a socket 13 to receive the rod 1 and a set-screw 14 to engage 65 said rod and hold the belt-shifting device fixed in adjusted position thereon. As shown in Fig. 1, the said belt-shifting device extends horizontally or at right angles to the rod, and the loop or eye 10 engages the adjacent stretch of the belt, so that by simply turning the handle 1^a in one direction or the other the rod 1 will be turned to swing the belt-shifting device longitudinally of the lathe and drive-shaft to shift the belt from the fast 70 to the loose pulley on the drive-shaft, and vice versa, as desired. By slidably mounting the fixed frame member or section 9 on the rod 1 and the adjustable frame-section 10 on said member 9 it is obvious that the belt-shifting device may not only be adjusted vertically to suit the elevation of the drive-pulley, but also horizontally toward and from the belt, so as to be adapted for application to belts varying in their distance from the rod 1. 75

Having thus particularly described my invention, what I claim, and desire to secure by Letters Patent, is—

In a belt-shifter, the combination with suitably-arranged pulleys having a belt thereon, 90 and an oscillating rod mounted in bearings, of a forked frame, a cross-head adjustable between the forks of the frame and having a socket for the passage of the rod, means coacting with said socket whereby to render the 95 frame adjustable on said rod, and a loop on said frame for the passage of said belt, substantially as specified.

In witness whereof I have hereunto set my hand in presence of two witnesses.

FRANK HIRSCH.
